CLAIM

The ornamental design for a protective guard for a stay-tab beverage can, as shown and described.

DESCRIPTION

FIG. 1 is front view of a protective guard for a stay-tab beverage can.

FIG. 2 is a back view of the protective guard for a stay-tab beverage can.

FIG. 3 is a right side view of the protective guard for a stay-tab beverage can.

FIG. 4 is a left side view of the protective guard for a stay-tab beverage can.

FIG. 5 is a top view of the protective guard for a stay-tab beverage can; and,

FIG. 6 is a bottom view of the protective guard for a stay-tab beverage can.

The shaded surfaces represent solid surfaces whereas the unshaded areas represent apertures.
